UNITED STATES PATENT OFFICE.

JOHN N. HIPSCHEN, OF BELLEVUE, IOWA.

BIN.

1,234,900.

Specification of Letters Patent.

Patented July 31, 1917.

Application filed April 29, 1916. Serial No. 94,455.

To all whom it may concern:

Be it known that I, JOHN N. HIPSCHEN, a citizen of the United States, residing at Bellevue, in the county of Jackson and State of Iowa, have invented certain new and useful Improvements in Bins, of which the following is a specification.

The invention relates to improvements in a bin, capable of use in various fields, such 10 for instance as in stores, or for use with ordinary household cabinets.

It is the object of the invention to provide a bin that is mounted within a casing and supported for a slight bodily movement 15 in a longitudinal direction as well as the usual tilting movement of which the bin is capable. Manifestly, many advantages are derived from a construction of this character, in view of the fact that when the bin is 20 moved bodily from the casing and then slightly tilted access can be had to substantially the entire interior thereof to permit the insertion of a relatively large scoop or like implement within the bin and allow the 25 removal of its contents.

My invention also comprehends the provision of a locking means of simple construction disposed within the casing and adapted to engage a portion of the bin when 30 the same is in a closed position to prevent the accidental tilting or moving of the bin, it being obvious that when the bin is left in an open position, which position it often accidentally occupies, the contents will rapidly 35 deteriorate, causing considerable unnecessary loss.

The preferred structure of the bin comprises a suitable casing having a movable carriage disposed therein and carrying suitable 40 rollers engaging a track within the casing. The carriage is capable of a substantial back and forth movement and has pivoted thereto at its forward end the lower portion of the bin so as to permit this bin to have a 45 tilting movement when the carriage has been moved outwardly to occupy its extended position. The bin, when in a horizontal position, is supported upon the surface of the carriage and is in no way connected directly to the casing, riding upon the carriage at all times during its back and forth movement.

Other objects and advantages will be hereinafter set forth, or more particularly pointed out in the accompanying specification.

In the drawings Figure 1 represents a vertical sectional view.

Fig. 2 is a similar view taken at right angles to Fig. 1, and

Fig. 3 is a horizontal sectional view.

Referring now more particularly to the drawings, wherein like numerals indicate corresponding parts, the numeral 1 designates suitable spaced supporting standards at the front of the casing, having arranged therebetween at their lower ends a relatively narrow cross piece 2. At their upper ends the standards are connected by a beam 3, and the space between the standards, cross piece and beam providing a door opening 4, 60 permitting the movement of the bin 5 into and out of the casing. The cross piece 2 and the beam 3 are attached to the standards by bolts or any suitable fastening devices. Projecting rearwardly from the standards 65 and lying flush with the top edge thereof, and extending to a point near their lower edges are the side pieces 6 of solid formation, having horizontal grooves at their lower ends into which the side edges of the 70 bottom 7 fit. The edges of the bottom by fitting within the horizontal grooves in the side walls of the casing prevent any lateral movement of the bottom. Locking strips 9 are secured to the sides of the casing and 75 directly underlie the bottom 7, these strips being of angular formation and also providing ample supporting means for the bottom. Fastening pins passing through the sides 80 also enter the bottom to securely attach it 85 to the side walls.

Attached to the rear edges of the side walls of the casing is the back 10, having a transverse slot 10' in its inner face fitting the inner edge of the bottom 7. The back is 90 reduced in width near each side edge at 11 so as to compactly fit the side walls of the casing and produce a casing having an attractive appearance, and assisting in properly centering the back to the casing. Extending across the back on its inner side near its upper edge is a relatively wide bar 12, having a vertically extending aperture 13 therein, through which a locking pin 14 passes. This locking pin enters a suitable 95 socket 14' within the upper edge of the bin 5 when the bin is in a closed position, or located entirely within the housing, and prevents the withdrawal of the same from the housing.

This has been found to be highly desirable as it prevents an unauthorized person from moving the bin to such a position as to allow the contents thereof to be exposed in view of the fact that the contents cannot be stolen or fingered by any unauthorized person. A suitable top 15 having a handle 13' is detachably secured to the casing by pivoted latches 16 engaging outstanding members 17 projecting from the top. This top is readily removable so as to permit the manipulation of the locking screw or pin 14 and allow the sliding carriage and bin 5 carried thereby to be moved to its extended position. Disposed within the casing is a carriage 18 having on its under side supporting rollers journaled in bearings 19' and engaging the tracks 20 positioned upon the bottom 7, at each side thereof, these tracks being shown as composed of flat strips of metal, although any suitable form of track may be used. The carriage is of considerable width, and entirely supports the bin 5 upon its surface, when the same is occupying its normal position, the surfaces of the carriage and the bottom of the bin being smooth and flat, the bin being pivoted near its center by suitable hinges to permit the same to be tilted when in its extended position. The carriage is permitted to have a substantial back and forth movement in view of the fact that the casing is much greater in length than the carriage so as to allow the bin to be moved in an open or closed position. To prevent any vertical movement of the carriage the guiding strips 21, consisting of rectangular blocks, are provided, which directly overlie the surface of the sides of the carriage and are disposed inwardly from the side walls of the casing. These guiding strips are so positioned within the casing as to prevent tilting or swinging of the carriage during its sliding movement, but when the carriage reaches its outermost position the bin is tilted in the usual manner to permit access to be had to its interior. Bracing members 22 carried by the sides of the casing overlie the guiding strips 21 and form an additional support therefor. These bracing members 22 also prevent any rocking movement of the bin when the same is within the casing, which tends to hold the bin firmly in its desired position and centers the same within the casing to prevent binding between the bin and casing during the sliding movement of the carriage and bin. The bin is pivoted intermediate its ends to the forward end of the carriage by hinge members 23, so that when the carriage has been moved to its extended position the bin is allowed to tilt in the usual manner. By pivoting the bin intermediate its ends it is easier to tilt the same into an open or closed position than if the bin were pivoted near one end in view of the fact that the contents of the bin serve

to counterbalance the same and render the tilting thereof a simple matter. While I have shown the usual type of hinge for pivoting the bin to the carriage, any convenient connection may be used without departing from the invention. The bin 5 is of the usual type, and instead of a bin a receptacle of any character can be pivoted to the carriage without departing from the invention. 70

When the bin has been moved to its forward position and is tilted, the tilting movement thereof is limited by a stop 24 having a beveled face 25, which engages the cross bar 2 disposed between the supporting standards 1. This stop projects from the lower wall of the bin and prevents the upper edges of the bin from contacting with the top beam of the casing so as to eliminate binding between the bin and the casing, and prevents the usual strain from being placed upon the beam 3, due to the heavy weight of the material in the bin. The inclined edge of the stop affords a relatively long engaging surface between the stop and the cross piece and prevents any friction between the casing and the bin when the same has been tilted. A handle 26 is attached to the face of the bin and provides means for withdrawing the bin from the casing. 95

The operation of the device may be briefly stated as follows: When it is desired to have access to the interior of the bin the locking pin 14 is removed and the handle 26 is grasped, the bin then being moved bodily from the casing upon the carriage 18, which travels over the tracks 20, upon the bottom until the forward edge of the carriage engages the standards, after which the bin, by a slight pressure, will tilt forward so as to allow access to the interior thereof to permit the removal of the contents. The bin by being pivoted to the carriage near its center is counterbalanced by the contents therewith so the same may be tilted much easier than usual, and may also be raised with equal ease so as to allow the same to be moved into its normal position. The backward movement of the bin is limited by the engagement of the door of the bin 5 with the standards 1, cross beam 2 and connecting bar 3, and when the bin is located within the housing the same rests entirely upon the carriage 18, and in fact is wholly supported by the carriage at all times. The return movement of the bin also causes the rear wall thereof to engage the rear wall of the casing 10, and this wall 10 as well as the cross piece 2 and connecting bars 3 constitute a stop therefor. 110

While I have illustrated my preferred embodiment of the invention, it is clearly apparent that many changes in the parts can be made without departing from the spirit of the invention. 125

What I claim is:

1. The combination with a casing, of a sliding carriage disposed within the casing and capable of a back and forth movement, a track for said carriage, antifriction means depending from the carriage and engaging said track, a guide within the casing overlying the carriage and preventing tilting thereof, a bin having a socket therein pivoted 10 at a point near its center to the carriage and adapted to rest thereon, the said bin when in its extended position adapted to be tilted with respect to the carriage to permit access to be had to the interior thereof, and a locking pin carried by the casing and adapted to enter said socket within the bin to lock the same in its closed position.
2. The combination with a casing having a bottom portion, of tracks disposed on said

bottom near each side, a carriage located 20 within the casing and capable of a sliding back and front movement, roller bearings journaled on said carriage and engaging the tracks, guiding blocks preventing tilting of the carriage, a bin pivoted to said carriage 25 at its forward end, and adapted to rest upon the carriage when in its normal position, the said bin when moved to its extended position adapted to be tilted to permit access to be had to the interior of the same, 30 and a stop carried by the bottom of the bin for limiting the tilting movement thereof.

In testimony whereof I affix my signature in the presence of two witnesses.

JOHN N. HIPSCHEN.
